UNITED STATES PATENT OFFICE.

SEBASTIAN PAINTMAIER, OF OXNARD, CALIFORNIA.

AUTOMOBILE-SIGNAL.

1,332,748.

Specification of Letters Patent.

Patented Mar. 2, 1920.

Application filed October 16, 1919. Serial No. 331,000.

To all whom it may concern:

Be it known that I, SEBASTIAN PAINTMAIER, a citizen of the United States, and a resident of Oxnard, in the county of Ventura and State of California, have invented a new and Improved Automobile-Signal, of which the following is a full, clear, and exact description.

This invention relates to improvements in automobile signals, and more particularly to a signaling device which is adapted to be secured to any convenient part of an automobile and operated by the chauffeur to indicate to other cars his intention as to the manipulation of his car.

In ordinary practice the hand or arm is used to indicate the intention of the chauffeur to cars in the rear, and it is the purpose of my invention to provide a device which can be readily operated to clearly signal such intention.

A further object is to provide a signaling device employing semaphore signals with improved means for operating the semaphores from an inclosed casing to a horizontally extended position and secure the semaphore in either of said positions.

A further object is to provide a signaling device which can be manufactured and sold at a reasonably low price, which will occupy but little space, which will not disfigure the car, which will be strong and durable in use, and which will most efficiently perform the functions for which it is intended.

With these and other objects in view the invention consists in certain novel features of construction, and combinations and arrangements of parts, as will be more fully hereinafter described and pointed out in the claims.

In the accompanying drawings—

Figure 1 is a view in vertical section illustrating my improvements;

Fig. 2 is a view in transverse vertical section on the line 2—2 of Fig. 1;

Fig. 3 is a view in transverse horizontal section on the line 3—3 of Fig. 1; and

Fig. 4 is a fragmentary face view showing the arrangement of buttons.

1 represents a casing which may be of any suitable material and is preferably of oblong shape. A transversely positioned rod 2 is secured in the upper portion of the casing and on this rod 2 a series of semaphores

55 A, B and C are pivotally mounted and are spaced apart by means of spacing collars 4.

It is, of course, apparent that the invention is not limited to any particular number of semaphores with their operating mechanisms, nor to the particular captions or manner of coloring or otherwise decorating the semaphores to convey the signaling intention. Three of such semaphore arms will, however, answer all practical purposes and a convenient means of indicating the intention of the operator is to provide the words Left, Stop and Right on the respective semaphores.

The casing 1 operates as an inclosure for the semaphores when they are in vertical position and one wall is slotted, as shown at 5, to provide sufficient space to allow the semaphores to be projected. Each semaphore is provided with a curved operating lever 7 and these levers 7 are pivotally mounted between their ends on a transverse rod 6 and separated by spacing collars 6'. These levers 7 at their upper ends are provided each with a tooth 8 which is adapted to enter a notch 9 in the end of the semaphore and hold the latter against accidental pivotal movement.

As the construction and operation of the mechanisms for each of the semaphores is precisely alike, the description hereinafter of one complete mechanism will apply alike to all.

A sliding plunger 10, preferably rectangular in cross-section, is mounted to move through the casing 1 and is supported on a platform 12 within the casing. The plunger 10 is connected by a pair of links 13 with the upper end of lever 7, and a block 14 is fixed in the upper end of the casing and is sufficiently narrow to allow the links 13 free movement at opposite sides thereof.

The block 14 supports a pin 15, which at its lower end projects into a longitudinal groove 16 in the plunger 10 and as the plunger fits between the lower end of the block 14 and the platform 12, it is held against any movement except a longitudinal one.

The plunger 10 is provided in its lower face with a socket 17 adapted, when the plunger is drawn outwardly, to move into position to receive a ball 18 upwardly pressed by means of a spring 19 in a housing 20 carried by platform 12 so that this ball 18 operates as a catch to engage the plunger and hold the parts against accidental move-

ment. When the plunger is in this position, the semaphore is thrown outwardly and held in a horizontal position and will be so maintained by reason of the action of the 5 ball 18 in the socket 17 until the plunger is forced inwardly. The plungers 10 at their inner ends outside of casing 1 are provided with buttons 11 and these buttons preferably contain the letters L, S and R, as shown 10 in Fig. 4, to indicate Left, Stop and Right, the captions of the semaphores to be operated.

The operation is as follows: When it is 15 desired to signal the proper plunger 10 is drawn outward and, through the medium of the links 13, the lever 7 will be swung on its pivot and its lower end will force the semaphore to a horizontal position, as indicated in Fig. 1. When the semaphore 20 reaches the horizontal position, the ball 18 will spring into the socket 17 and maintain the parts in this position until the plunger is again forced inwardly when the semaphore will fall to a vertical position and the 25 tooth 8 on the end of the lever 7 will move into the notch 9 in the end of the semaphore and hold the latter against accidental swinging movement.

Various slight changes may be made in 30 the general form and arrangement of parts described without departing from the invention, and hence I do not limit myself to the precise details set forth but consider myself at liberty to make such changes and 35 alterations as fairly fall within the spirit and scope of the appended claims.

I claim:

1. A signaling device of the character 40 stated, comprising a casing, a plurality of semaphores pivotally mounted in the casing and movable through the casing, a pivoted lever for each semaphore projecting above and below the pivot point of the semaphore, a sliding plunger for each semaphore, links 45 connecting the plungers and the levers, and said levers adapted, when the plungers are moved outwardly, to engage the semaphores and force them out of the casing.

2. A signaling device of the character 50 stated, comprising a casing, a plurality of semaphores pivotally mounted in the casing, a curved lever for each semaphore, said levers pivotally supported between their ends and projecting above and below the pivot 55 points of the semaphores, one end of the lever adapted to engage the semaphore and force the latter outwardly from the casing and the other end of said lever adapted to engage the end of the semaphore, when the 60 latter is in the casing, and hold the semaphore against movement, and means for operating the levers.

3. A signaling device of the character 65 stated, comprising a casing, a plurality of semaphores pivotally mounted in the casing,

a curved lever for each semaphore, said levers pivotally supported between their ends and projecting above and below the pivot points of the semaphores, one end of the lever adapted to engage the semaphore and 70 force the latter outwardly from the casing and the other end of said lever adapted to engage the end of the semaphore, when the latter is in the casing, and hold the semaphore against movement, a plunger for each 75 lever, and links connecting the plungers and the levers.

4. A signaling device of the character stated, comprising a casing, a plurality of 80 semaphores pivotally mounted in the casing, a curved lever for each semaphore, said levers pivotally supported between their ends and projecting above and below the pivot points of the semaphores, one end of the lever adapted to engage the semaphore and 85 force the latter outwardly from the casing and the other end of said lever adapted to engage the end of the semaphore, when the latter is in the casing, and hold the semaphore against movement, a plunger for each 90 lever, links connecting the plungers and the levers, and means for holding the plunger in a position to project the semaphore.

5. A signaling device of the character 95 stated, comprising a casing, semaphores normally in the casing, curved levers pivotally mounted between their ends and projecting above and below the pivot points of the semaphores, one end of a lever engaging the side of the semaphore, whereby the movement of the lever in one direction operates to project the semaphore from the casing, said semaphores having notches in their ends, said levers having teeth at their ends adapted to engage in the said notches and 105 hold the semaphores in the casing, and means for operating the levers.

6. A signaling device of the character 110 stated, comprising a casing having slots therein, semaphores pivotally mounted in the casing and movable through said slots, levers operatively connected with the semaphores, a platform in the casing, blocks in the casing spaced from the platform, plungers movable between the platform and the 115 blocks, links connecting the levers and the plungers, and means for preventing turning movement of the plungers.

7. A signaling device of the character 120 stated, comprising a casing having slots 125 therein, semaphores pivotally mounted in the casing and movable through said slots, levers operatively connected with the semaphores, a platform in the casing, blocks in the casing spaced from the platform, plungers movable between the platform and the blocks, links connecting the levers and the plungers, said plungers having longitudinal 130 grooves therein, and pins in the blocks projecting into the grooves.

8. A signaling device of the character stated, comprising a casing having slots therein, semaphores pivotally mounted in the casing and movable through said slots, 5 levers operatively connected with the semaphores, a platform in the casing, blocks in the casing spaced from the platform, plungers movable between the platform and the blocks, links connecting the levers and the 10 plungers, each plunger having a notch in its lower face, and spring pressed balls carried by the platform and adapted to engage in said notches when the plungers are drawn outwardly.
9. A signaling device of the character 15 stated, comprising a casing having slots therein, semaphores pivotally mounted in the casing and movable through the slots, levers for moving the semaphores, said levers pivotally supported between their ends 20 and extending at their ends above and below the pivot points of the semaphores, plungers movable through the casing and operatively connected with the levers, buttons 25 on the outer ends of the plungers, and said buttons and semaphores containing captions corresponding with each other.

SEBASTIAN PAINTMAIER.
